UNITED STATES PATENT OFFICE.

EDWARD H. AIKIN, OF LOCKPORT, NEW YORK.

SNOW-REMOVING APPARATUS.

Application filed August 11, 1924. Serial No. 731,449.

My present invention pertains to snow removing apparatus of the type including a scraper that is moved in front of a motor vehicle and is disposed at an angle to the line of traverse so as to scrape snow from its path and deposit the snow at one side of the said path.

The general object of my said invention is to improve snow removing apparatus of the kind indicated by the provision of means for relieving the scraper of its overload, so that instead of snow piling up in front of the rear end of the scraper and impeding the progress of the scraper, the snow collected at said point is struck and expelled to one side of the path of the scraper.

Other objects and practical advantages of the invention will be fully understood from the following description and claim when the same are read in connection with the drawings, accompanying and forming part of this specification, in which:—

Figure 1 is a top plan view illustrative of one preferred embodiment of my invention.

Figure 2 is an enlarged detail front elevation showing the arrangement of my novel rotary expelling means relative to the scraper.

Figure 3 is a vertical section taken in the plane indicated by the line 3—3 of Figure 2.

Figure 4 is a detail front elevation of the comparatively large expeller.

Figure 5 is a similar view of the small expeller.

Figure 6 is a view taken at right angles to Figure 4 and showing the large expeller.

Figure 7 is a view of the small expeller taken at right angles to Figure 5.

Figure 8 is a top plan view illustrative of another preferred embodiment of my invention hereinafter explicitly referred to.

Figure 9 is a detail view of a rotary expeller provided with detachable blade portions.

Similar numerals designate corresponding parts in Figures 1 to 7 to which reference will first be made.

The scraper 1 illustrated is of the ordinary well known concavo-convex kind, though it may be of any other suitable construction compatible with the purpose of my invention. As shown in Figure 1 the said scraper 1 is pivotally connected at 2 with a frame 3 on the front axle of a motor

vehicle 4, and the scraper is equipped with an arcuate apertured member 5 for cooperation with a removable pin 6 through the medium of which the scraper can be adjustably fixed at various angles to its line of traverse. The said construction is also of such character that the scraper 1 can be reversed, and in this connection I would have it understood that my improvement is carried on the scraper in such manner that it is feasible to shift the expelling means hereinafter described from the right hand end of the scraper 1 in Figure 1 to the left hand end of said scraper 1 and vice versa. I would also have it understood that the scraper 1 is suspended in conventional manner from elevated means on the front portion of the tractor. This latter, however, is not of my invention, and I therefore deem it unnecessary to illustrate the same, my invention residing in the combination with the scraper of expelling means located in front of the rear end of the scraper in the manner and for the purpose before indicated.

In accordance with the embodiment shown in Figure 1 an appropriate supporting frame 7 is fixed to and disposed in rear of the upper portion of the scraper 1, and the said frame 7 is provided with appropriate bearings 8 to receive a shaft 9 on which is fixed a rotary expelling means—i. e., means for kicking or throwing the snow collected in front of the said end of the scraper a considerable distance at one side of the scraper path when the same is moved forwardly in front of a motor vehicle. The said expelling means is preferably, though not necessarily, made up of a large rotary expeller 10 and a comparatively small rotary expeller 11, the latter being disposed in front of the former and being designed to assist the large expeller 10 and to relieve the same of a considerable portion of the work when a heavy snowfall is being handled. The said rotary expellers 10 and 11 are shown in detail in Figures 4 to 7 and by reference to said views it will be understood that each of the expellers comprises a hub 12 that is appropriately fixed to the shaft 9 and three equi-distant blades 13, the said blades 13 being designed to be moved in anti-clockwise direction and being provided at their backs with longitudinal ribs 14. The shaft 9 is provided at 15 with a sprocket gear, and the said sprocket gear is connected by a sprocket belt 16 with

a sprocket gear 17 on the shaft of a motor or engine also carried on the frame 7, and which motor or engine may be an electric motor or a motor or engine of any other appropriate type. An electric motor is shown at 18 and the sprocket gear 17 is fixed to its armature shaft 19. I would also have it understood that the motor 18 may be supplied with current by any appropriate means (not shown), and that the motor and the rotary ejecting means may be shifted on the frame 7 to adapt the rotary expelling means for use when the scraper is reversed as before indicated.

15 It will be apparent from the foregoing that in the practical use of a scraper such as 1 associated with my novel ejecting means, the scraper is moved in front of the motor vehicle with the result that snow in front of the scraper tends to move from the left hand end of the scraper in Figure 1 toward the right hand end of said scraper. As soon as the snow so moved relative to the scraper 1 is within reach of my novel rotary ejecting means, the said snow will be engaged by the blades 13 and thrown to one side of the path of the scraper 1 with the result that a collection of snow in front of the rear end of the scraper 1 is precluded and hence the said scraper 1 can be moved steadily forward for the making of a clear path. It will also be noticed in this connection that in virtue of the employment of my novel expelling means the formation of a deep ridge of snow at one side of the path cleared by the scraper 1 will be obviated which is manifestly an important advantage, particularly when it is desired to widen the cleared pathway by a scraper moved in rear of the one illustrated.

In the modification shown in Figure 8 scrapers 1^a at obtuse angles to each other are appropriately connected with a motor vehicle 4^a, and the rotary expellers 10 and 11 are arranged in front of the outer and rear ends of the said scrapers 1^a. In said embodiment of Figure 8 the rotary expellers are carried on shafts 9^a, journaled in bearings on frames 7^a fixed to and carried in rear of the scrapers 1^a, and the said shafts 9^a are connected through universal joints 30 with rearwardly converging shafts 31. These shafts 31 are connected, in turn, by universal joints 32 with shafts 33, journaled in bearings 34^a on the motor vehicle 4^a. Carried on the said motor vehicle 4^a is an auxiliary engine or motor 18^a which may be of any type compatible with the purpose of my in-

vention, and the drive shaft 19^a of the said motor is equipped with beveled gears 34 and 35, the gear 34 being meshed with a gear 36 on one shaft 33, and the gear 35 being meshed with a gear 37 on an auxiliary shaft 38 which latter is also provided with a spur gear 39 meshed with a gear 40 on the other shaft 33. Manifestly when the motor 18^a is actuated and the motor vehicle 4^a is moved forwardly the rotary expellers 10 and 11 will operate in association with the scrapers 1^a in the same manner and for the same purpose as the rotary expellers 10 and 11 of Figure 1. Incident to the operation of the embodiment shown in Figure 8, however, the snow will be expelled to opposite sides of the pathway formed by the plow or pair 75 of scrapers 1^a and hence there will be no ridges or comparatively deep portion of snow left at either side of the course traversed by the plow formed by the scrapers 1^a. From the embodiment disclosed in Figure 8 it will be readily appreciated that my improvement is readily applicable to snow scrapers or plows such as are employed in front of railway locomotives.

It will be appreciated from the foregoing that notwithstanding the highly useful purpose performed by my improvement, the said improvement is simple and inexpensive in construction and is well adapted to withstand the usage to which snow removing apparatus is ordinarily subjected.

Having described my invention, what I claim and desire to secure by Letters-Patent, is:—

The combination with a motor vehicle of a frame extending from and secured to the front of said motor vehicle, an arcuate apertured member secured to the frame and mounted thereon for movement in a horizontal plane, a frame carried by the arcuate apertured member for movement therewith, a scraper secured to the front of the second mentioned frame, a removable pin carried by the arcuate shape member and adapted for association with the frame first mentioned whereby the scraper can be adjustably arranged at various angles to its line of traverse, a motor on the frame second mentioned, a shaft also carried by the frame second mentioned, a pair of rotary blade carrying expellers of different sizes on said shaft and means between said motor and the shaft respectively for revolving said expellers.

In testimony whereof I affix my signature.
EDWARD H. AIKIN.
